DRILL CARRIAGE

Charles A. R. Lambly and Lindsey Kinney,
Metaline Falls, Wash.

Application May 21, 1946, Serial No. 671,376

2 Claims. (Cl. 255—51)

1

The present invention relates to drill carriages. It is the principal purpose of our invention to provide a novel carriage which is designed to carry one air drill and to be taken into drifts or raises or stopes in mining with a minimum amount of difficulty. The carriage as constructed can be taken up or down slopes of as great as 30 degrees with the drill mounted thereon, and can be moved over rock piles with the drill mounted.

A principal purpose of our invention is to provide a carriage of this character which is composed of two main frame members both bent at a point intermediate their ends and connected together only at their ends so as to form a rigid structure which presents minimum obstruction to the operator of the drill. Suitable supporting wheels are mounted at the bends so that the wheels and the two end portions of the frame members extend away from each other at such angles that the wheels and either end of the frame may serve as ground engaging supports.

It is a further purpose of our invention to provide a carriage of this character with means to clamp a drill frame thereto so that the drill can be used to drill holes in a rock face at different levels above the floor at any desired angle to the horizontal, the same carriage being operable to support the drill at the floor level so that flat holes may be drilled near the level of the floor without disturbing the mounting of the drill on the carriage.

The novel features that we consider characteristic of our invention are set forth with particularity in the claims. The invention itself, however, both as to its organization and its method of operation, together with additional objects and advantages thereof, will be understood from the description of a specific embodiment when read in connection with the accompanying drawings, in which:

Figure 1 is a view in side elevation of a drill carriage constructed in accordance with our invention;

Figure 2 is a similar view illustrating the carriage with the drill lowered to position to accomplish drilling at the floor level;

Figure 3 is a perspective view of the carriage with the drill mounted thereon;

Figure 4 is a fragmentary sectional view taken at one side of the drill frame to illustrate the manner in which it is clamped upon the cross bar of the carriage; and

Figure 5 is a sectional view taken on the line 55

2

5—5 of Figure 2 illustrating the manner of mounting the wheels to the carriage.

Referring now in detail to the drawings, our invention is embodied in a drill carriage which is characterized by its extreme simplicity. The carriage is adapted to support an air drill for use in drilling holes in tunnels and is particularly adapted for mining work. A carriage for this purpose should be light in weight yet strong and it should be easily movable so that it can be taken up or down relatively steep slopes, over rock piles and yet supported solidly when the drill is being used. The carriage embodying our invention is simple in construction so that it is very light. It consists of two side frame members 10 and 11 which desirably are constructed of pipe or tubing, the frame members being bent as shown at 12 and 13 at a point about one-third of the way from one end thereof. The angle of bending preferably is in the neighborhood of 75 degrees. The pipe members 10 and 11 desirably are somewhat deformed in the bending so as to provide spaced apart ribs 14 adjacent to the bend. These ribs are exaggerated in the drawing. The purpose of forming the ribs 14 and the depressions 15 therebetween is to provide sockets in which a clamp bar on the frames for the supporting wheels may be located and secured. These ribs and sockets may be left off if desired. The said frame members 10 and 11 are connected together by a drill supporting bar 16, the bar 16 is welded or otherwise rigidly secured to the short ends of the frame members from the bend. At the other ends of the frame members a handle bar 17 serves to connect the members, the bar 17 being welded in place. It will be understood of course, that the drill supporting bar 16 and the bar 17 are constructed of pipe or tubing like the members 10 and 11. The entire frame preferably is connected together by welding the members 10, 11, 16, and 17 to each other wherever they meet.

A drill frame 18 is adapted to be secured to the bar 16 so as to support an air drill 18a on the carriage. The frame 18 has a head 19 secured upon a mounting block 20. The block 20 has a fixed jaw 21 and a sliding jaw 21a to engage the head 19 and secure the drill frame to the block 20. The block 20 is in turn clamped to the bar 16 by a cooperating clamping member 22 and clamping bolts 23.

The construction of the drill mount is such that were it desired to obtain a different level than that provided by the two positions shown in Figures 1 and 2, a longer column of the desired

length with a head 19 can be secured on the frame 18 and utilized to raise the drill frame more or less above the level of the block 20 to permit supporting of the drill at any elevation from the floor level shown in Figure 2 up to a level substantially higher than that shown in Figure 1. As an example of the range to which the carriage is applicable, the drill may be supported by the use of the two positions shown in Figures 1 and 2, at about four feet above the floor or substantially at the floor level, then by using a column to raise the drill frame above the level of the block 20, the drill can be raised to any desired height up to about nine feet.

The construction by which the carriage is given wheel support comprises two rubber tired wheels 24 and 25. These wheels are journaled in brackets 26 and 27 which are substantially U-shaped. The U-shaped brackets may be made of flat steel bar stock bent to the proper shape. These brackets are clamped to the members 10 and 11 by utilizing a separate clamping bar 28 which is secured on the top of the bracket and bent upwardly and around the pipe and then downwardly parallel to the near leg of the bracket where it is further secured to form a firm mounting on the pipe member.

It is believed that the construction of our drill carriage will be clear from the foregoing description and the accompanying drawings. The total weight of the carriage need not exceed 100 pounds in order to give adequate strength for our purposes. The carriage when the drill is mounted in position for use can be moved to the rock face to be drilled. The drill itself is also mounted as to be substantially balanced on the cross bar 16 so that if it is desired to support the carriage the handle bar 17 is raised to a comfortable level for a man to grasp it and the drill is secured level in this position. The carriage can then be pushed or pulled like a two wheeled cart. When the carriage is moved to operating position the carriage handle is then set on the ground or floor adjacent the rock face to position the drill as shown in Figure 1 so as to drill a hole in the rock face at the desired level above the floor. Different heights can be obtained by having longer or shorter frame members 10 and 11, or by using different length columns to carry the drill. The drill of course, can be swung on the member 16 to get the proper angle to the horizontal on any desired hole that is to be drilled. By swinging the drill on its pivot in the block 20, any combination of angles can be obtained for drilling a hole that may be needed.

When it is desired to drill holes at the foot of a bench or tunnel, on the floor level, the handle of the carriage is raised up until the drill column rests on the ground or floor. The drill is then in position to drill flat holes on the level of the floor. In order to get intermediate hole level or to drill

the holes in the face at a higher level, it is necessary to support the drill on a column above the cross bar 16.

Having thus described our invention we claim:

1. A drill carriage comprising two parallel tubular side bars, a cross bar at each end of the bars rigidly connecting them, the side bars being bent in the same direction at an intermediate point about one-third of the length thereof so that the portion adjacent one cross bar extends at an angle of about 75 degrees to the other position, a drill mount on the cross bar at the short end portion, the other cross bar serving as a handle, and individual wheel supports for the side bars, each comprising an inverted U-shaped frame having a wheel axle at the ends of the legs thereof and a wheel mounted thereon between the legs, a clamping bracket for each frame extending over the corresponding side bar at the bend and secured to the U-shaped frame holding the frame rigidly outward at an angle of more than 90 degrees to both portions.

2. A drill carriage comprising two parallel tubular side bars, a cross bar at each end of the bars rigidly connecting them, the side bars being bent in the same direction at an intermediate point about one-third of the length thereof so that the portion adjacent one cross bar extends at an angle of about 75 degrees to the other portion, a drill mount on the cross bar at the short end portion, the other cross bar serving as a handle, and individual wheel supports for the side bars, each comprising an inverted U-shaped frame having a wheel axle at the ends of the legs thereof and a wheel mounted thereon between the legs, a clamping bracket for each frame extending over the corresponding side bar at the bend and secured to the U-shaped frame holding the frame rigidly outward at an angle of more than 90 degrees to both portions, the side bars having spaced ribs inside the bend between which the clamping bracket is seated.
